DESIGN FOR AN ADSORBER

Enrique L. Luaces, Dayton, Ohio, assignor to The Commonwealth Engineering Company of Ohio, Dayton, Ohio, a corporation of Ohio

Application June 16, 1942, Serial No. 107,220

Term of patent 14 years

To all whom it may concern:

Be it known that I, Enrique L. Luaces, a citizen of the United States, residing at Dayton, in the county of Montgomery and State of Ohio, have invented a new, original, and ornamental Design for an Adsorber, of which the following is a specification, reference being had to the accompanying drawing, forming a part thereof, wherein:

Fig. 1 is a top plan view of an adsorber showing any new design; and

Fig. 2 is a side elevational view thereof.

The side opposite that shown in Fig. 2 is substantially like that shown in said Fig. 2.

I claim:

The ornamental design for an adsorber, substantially as shown and described.

ENRIQUE L. LUACES.
